H. R. HUGHES.
ROTARY DRILL CUTTER.
APPLICATION FILED OCT. 28, 1920.

1,412,003.

Patented Apr. 4, 1922.

HOWARD R. HUGHES - INVENTOR.

BY *Jesse R. Stone*

ATTORNEY.

UNITED STATES PATENT OFFICE.

HOWARD R. HUGHES, OF HOUSTON, TEXAS.

ROTARY DRILL CUTTER.

1,412,003.

Specification of Letters Patent. Patented Apr. 4, 1922.

Application filed October 28, 1920. Serial No. 420,257.

To all whom it may concern:

Be it known that I, HOWARD R. HUGHES, a citizen of the United States, residing at Houston, Harris County, Texas, have invented a certain new and useful Improvement in Rotary Drill Cutters, of which the following is a full, clear, and exact description, such as will enable others skilled in the art to which it appertains to make 10 and use the same.

My invention relates to an improvement in cutters for use on roller boring drills and has especial application to earth boring drills for use in drilling wells for water, oil, 15 gas, sulfur, etc.

In drills of this type there is usually a head, approximately cylindrical in shape having on the forward end thereof a cutter or cutters mounted on axes that are horizontal or nearly so, said cutters being adapted 20 to roll on the bottom of the well and to disintegrate the material by a combined chisel and scraping action. The chisel action is due to the successive strokes of the teeth of 25 the cutters upon the bottom of the hole as the cutter rolls rapidly thereon. The scraping action is due to the fact that the cutters are rolling in a circle of a diameter either 30 too small or too large to accommodate the size of the cutter. As a result of this fact, it has not, at all points, a true rolling motion upon the bottom of the hole, but tends to 35 slip or scrape upon the material.

An object of my invention is to so form 35 the teeth upon the cutter as to obtain the greatest possible disintegrating action upon the material being drilled.

Another object is to form a cutter with a plurality of cutting zones thereon, each 40 of which is so formed as to act most effectively upon that portion of the bottom of the hole upon which it travels.

These and other objects and advantages 45 will more clearly appear from the detailed description which follows.

Referring to the drawings, wherein are shown various embodiments of my invention, Fig. 1 illustrates, in perspective, a cutter of cylindrical type having the teeth 50 formed thereon according to my invention.

Fig. 2 is a top plan view of said cutter. Fig. 3 is a plan view of a slightly different modification of my invention. Figs. 4, 5 and 6 show my invention applied to va-

rious other forms of cutters and Figs. 7, 8, 55 and 9 illustrate different forms of teeth to be used in connection with the application of my invention. Like numerals are applied to like parts throughout the several views.

In forming the teeth upon the cutters to 60 be used with rotary boring drills, I have shown in Figs. 1 and 2 a type of cutter which is commonly used with such devices. In Fig. 1 the cutter is shown as rotating on an axis 9 and traveling in a circular orbit 65 about the center O, this point O representing the vertical longitudinal axis of the head of the bit upon which the cutter is mounted. The cutter travels about this central axis O in the direction of the arrow adjacent thereto in a clock-wise direction. As the cutter rolls in this circular track about the center of the bit, the forward face thereof is moving downwardly, as indicated by the arrow 70 upon the cutter. The position of the cutter 75 relative to the central axis O has been so arranged that a central vertical plane 12 on said cutter will be in such position as to have a true rolling motion about the central axis 80 of the bit and forms in this way a neutral plane between the inner half 11 and outer half 10 of the cutter, neither of which have a true rolling motion. As the cutter is cylindrical in general outline the inner half 11 85 of the cutter will be traveling faster than is necessary to keep up with the outer half which is traveling in a circle of larger diameter than the inner half. Due to the fact 90 that the two halves are integrally joined and both therefore make the same number of revolutions in traveling about the center of the bit, there will be a slipping of the inner half 11, thereby allowing the inner half to keep pace with the outer, and likewise on the outer half 10 there will be a slipping, but 95 in an opposite direction. It will be obvious on inspection that the slipping on the inner half of the cutter will be in a forward direction, that is in the direction of rotation of the cutter. The teeth 14, formed on the 100 inner half 11, will, therefore, be shaped to present a sharp advancing edge to better disintegrate the material at the bottom of the hole. (See Fig. 8.)

Likewise the outer half of the cutter in 105 its rotation will have a slipping as it will tend to lag behind the neutral plane 12 and its direction of slipping will be in a direc-

tion contrary to that of the rotation of the cutter and the teeth 15 on the half 10 will, therefore, be cut to present the sharp cutting edge in the direction of slippage, as shown 5 in Figs. 1 and 7.

The particular form of tooth shown in the drawing has a radial forward face 16 and the rearward face thereof is beveled 10 backwardly and inwardly from the outer edge of the face 16, in such manner as to reinforce and strengthen the tooth as much as possible. For this purpose it has a rearward face 17 inclined only slightly, and a second beveled portion 18, inclined at a still 15 sharper angle, down to meet the forward face of the tooth next adjacent thereto. While this form of tooth is shown and described in the drawing, it is understood, however, that this particular form is not the 20 only form which this tooth might assume, but that it may be varied as desired with the object of presenting the sharp edge of the tooth toward the direction of slippage of the surface upon which the tooth is cut.

25 In the form illustrated in Figs. 1 and 2, the cutter, in rolling about the central axis of the bit, will strike the bottom of the hole with a sharp chisel stroke as each successive tooth comes in contact with the material.

30 Also there will be a scraping or shearing action of the teeth upon the bottom of the hole, due to the slipping of the cutting surface, because of the fact already explained, that the surfaces do not have a true rolling motion, but tend to slip on the bottom of the 35 hole. The inclination of the teeth is such as to give with the slipping action a most efficient scraping or cutting of the material as the cutter rotates.

40 In Fig. 3 I have shown a cutter having three cutting zones, an inner zone 11 and an outer zone 10 in the same manner as disclosed in Fig. 2, but having in place of the neutral dividing plane 12 an approximately 45 neutral zone 19 between the two cutting zones 10 and 11. The teeth upon the zones 10 and 11 are cut as described in reference to Figs. 1 and 2 to present the sharp edge of the tooth in the direction of slippage upon the bottom of the hole. The central zone 19, which has only slight slipping action, is 50 formed with teeth 20 which are approximately symmetrical, as shown particularly in Fig. 9. As will be noted the teeth 20 will 55 cut equally well in either direction of rotation of the cutter.

In Fig. 4 I have shown a modification 60 wherein my invention is applied to a cutter frusto-conical in outline. The smaller circumference of the said cutter is presented toward the central axis of rotation of the bit, but as the outer surface is not so tapered as to bring the apex of the cone, of which the 65 cutter is a part, at the central axis of rotation of the bit, there is still the same slip-

ping action as indicated in the cylindrical type of cutter. The outer half 10 of the cutter makes the same number of revolutions as the rest of the cutter, and at the same time travels in a larger circumference, and 70 hence is compelled in keeping up with the rest of the cutter to slip upon the bottom of the hole in a clock-wise direction. The inner half of the cutter on the other hand is traveling relatively faster than is necessary 75 to keep up with the rest of the cutter and is compelled to slip upon the bottom of the hole in the opposite direction. The teeth, therefore, on the cutter 4 are formed upon the periphery of the cutter in the same manner as those previously described relative to 80 Figs. 1 and 2.

In Fig. 5 a cutter is shown having the inner half thereof of a smaller diameter than the outer half, both halves being cylindrical 85 in outline, but, as was explained in connection with Fig. 4, the relative size of the inner and outer halves of the cutter is still such that the cutter has not a true rolling motion at any point except upon the neutral 90 plane 12''. The teeth are, therefore, formed upon the outer and inner halves of the cutter as they were described relative to Figs. 1 and 2, the teeth upon the outer half of the cutter being inclined backwardly from the direction of rotation of the cutter and those upon the inner half being inclined forwardly in the direction of rotation thereof.

Fig. 6 illustrates another embodiment closely like that shown in Fig. 2 but differing therefrom only in the fact that the periphery of each half of the cutter is rounded somewhat, as shown in a longitudinal section through the cutter, this rounded periphery serving to act more efficiently upon different formations. The purpose of this view is to show merely that this method of forming the teeth upon the cutting periphery of the cutter is not confined to any particular type or shape of cutter, but may be applied 100 with equal success to varied and different types of cutter.

As will now be readily seen a cutter formed with teeth cut thereon in the manner described will tend to act more rapidly and 115 efficiently upon the material and to disintegrate the same more rapidly than teeth of the ordinary construction. The inclination of the teeth so that the sharp cutting edge thereof will be presented in the direction 120 that the slippage occurs upon the bottom of the hole will act to perform the usual function of the teeth, that is to strike the bottom of the hole with a chisel stroke and will, in addition, act to scrape and shear the material thus being drilled and more rapidly 125 wear and disintegrate the formation. The advantages of this type of cutter will be obvious to one skilled in the art without further explanation.

Having thus described my invention, what I claim as new and desire to protect by Letters Patent is:

1. In a roller drill, a cutter adapted to roll on the bottom of the hole with a slipping action of the cutting surface relative to the bottom of the hole, said cutter having teeth thereon cut transversely of the periphery of the cutter, the teeth on one portion being inclined rearwardly and those on the other portion inclined forwardly in the direction of rotation of the cutter so as to engage the bottom of the hole most effectively as the teeth slip thereon. 35
2. In a roller boring drill, a rolling cutter with its periphery shaped to avoid a true rolling action at each end thereof, said cutter having transverse peripheral teeth thereon, the teeth on one end of the peripheral surface being inclined forwardly and those on the other end being inclined rearwardly relative to the direction of rotation of the cutter to most effectively engage the bottom of the hole as the teeth slip thereon. 40
3. In a roller boring drill, a rolling cutter having peripheral teeth thereon, the teeth on the outer end of the peripheral surface being inclined rearwardly and those on the inner end being inclined forwardly in the direction 45 of rotation of the cutter.

4. In a roller boring drill, a cutter adapted to roll on the bottom of the hole with a slipping action actuated by the rotation of the drill and teeth formed on the peripheral surface of said cutter with a sharp cutting edge which is inclined in the direction of slippage of said surface as the cutter rolls on the bottom of the hole. 50

5. In a roller boring drill, a cutter adapted to roll in a circular path on the bottom of the hole, teeth on the periphery of said cutter so formed as to provide a neutral plane approximately midway between the ends thereof and having the teeth on the outer side of said neutral plane so cut as to present a sharp scraping edge rearwardly and those on the inner side forwardly in the direction of rotation of the cutter. 55

6. In a roller boring drill, a roller cutter constrained to roll upon the bottom of the hole by the rotation of the drill, and teeth on the periphery of said cutter, those on one end being inclined forwardly in the direction of rotation and those on the other end inclined in the opposite direction in the manner and for the purpose described. 60

In testimony whereof, I hereunto affix my signature, this the 22nd day of October, A. D., 1920.

HOWARD R. HUGHES.
